ETHELBERT FAVARY, OF EAST BOSTON, MASSACHUSETTS.

LOCKING DEVICE.

1,146,317.

Specification of Letters Patent. Patented July 13, 1915.

Application filed August 28, 1909. Serial No. 515,015.

To all whom it may concern:

Be it known that I, ETHELBERT FAVARY, subject of the King of Hungary, and residing at the Maverick House, city of East 5 Boston, State of Massachusetts, have invented certain new and useful Improvements in Locking Devices, of which the following is a specification.

This invention relates to means for locking two relatively moving members in a mechanism, as by lateral sliding, or parts relatively moving by one turning with relation to the other; and has for its object the holding of the moved part fixedly in position, except when movement is imparted to 15 it by an operating element.

This invention is applicable to a great variety of devices used for different purposes, but particularly for the locking of 20 operating levers for the control of valves, operation of brakes, or any parts to be set in a plurality of positions, and particularly to supplant use of levers in the locking of which it has been common practice to use a 25 notched segment. My device permits the locking of such operating or adjusting levers or parts in an infinite number of positions, not limited by a predetermined number of notches as in the case of a notched segment.

While locking devices of this general character have been heretofore suggested, my invention resides in the simplification, 30 the relative arrangement of parts and the efficiency with simplicity of construction, affording a secure locking means with the aforesaid infinite number of possible positions.

In the drawings attached hereto and forming a part hereof, I have illustrated 40 specific embodiments of my invention.

Figure I is a lateral view of casing with part of cap removed, showing an operating lever, an operated and intermediate locking mechanism. Fig. II is a vertical section 45 through Fig. I. Fig. III is a top view of the locking casing with part of the shell broken away. Figs. IV and IV² are views similar to Fig. III, with modified releasing means. Fig. V is a view similar to Fig. I 50 with modifications in detail. Fig. VI is a vertical section of Fig. V, while Fig. VII is a top view of Fig. V. Fig. VIII is a plan view of a modified form of operating lever arrangement. Fig. IX is a section of Fig.

VIII showing detail of modified form of 55 locking means.

In the figures, C is an operating lever, B an operated part which is locked to or integral with the hub or cam D. The operated part B may be rotatively locked or secured to cam D by means of the shaft A.

Lever C is connected or integral with a plate or part C', which carries one or more pair of depending arms, C''. A casing, A', is fixed as by a base, A'', against rotation 60 and constitutes an anchor for locking purposes.

A locking means, such as ball E is located between the outer surface of block D, and the inner surface of fixed casing A', contacting with two surfaces on block D, each of which two surfaces is inclined toward the inner surface of the casing A', so as to constitute a cam face and engage the ball E to lock block D to casing A' by jamming 75 the locking ball E between the two surfaces. The material of these engaging parts and their frictional qualities determines the relative angularity of these two surfaces.

The arms or dependent members C'', extend on either side of the locking means E, terminating in a toe or extension proportioned and fashioned to engage the ball or locking means E, upon a slight relative movement of the operating handle C.

A spring F, between the ball and cover or part C', tends to force the locking means, ball E, between the casing and the hub or cam member D, into locking contact.

Between lever C and plate C' and the operated part and the cam D, there is a slight relative movement limited by the engagement of dependent members C'' C''', with projection D' on D.

In the form shown in Figs. IV and IV², 95 the toes or means for releasing the ball locking are attached pivotally to the operated hub D. The plate C' has depending lugs c and these engage the releasing toes C'' to pivot them slightly on their connection to 100 the hub D.

In the form shown in Figs. V, VI and VII, the operating lever C having the plate C', has the projecting lug D', which as seen in Fig. VII has beveled edges engaging projections on a plate D''. A spring F engaging a nut on the shaft A, presses the plate C' onto the plate D''. Conical locking

means E' is in this way forced into contact with the conical inner face of casing A', and the conical face of hub D at a point where the face of hub D has a reentrant surface 5 face D'''.

In Figs. VIII and IX, a modification of the construction just described is shown, in which a conical locking means is forced normally downward by the spring F', and a reentrant surface on the hub D of the operated member engages the cam to effect a locking between it and the inner face of casing A'. The lever C is pivoted so that a lateral instead of a rotary movement releases the locking means.

The operation of the device is as follows: Upon the movement of the handle C the slightest rotation of plate C' and depending parts C'', will bring the toe of the depending part in contact with the locking means as ball E, and due to the angularity of the engaging toe will force the ball or locking means upward and thereby out of the locking position against the action of the spring. The continued rotation of the lever C results in engagement with the member D' of the operated parts, thereby moving the operated lever B to any desired position. Upon the release of operating lever C the spring F immediately forces the ball or locking means into a position securely locking hub or cam block D against rotation in either direction. It will be seen that by this construction I obtain with a single ball a secure locking against rotation in either direction of an operated part. Similarly, a single conical cam, shown at E' in Figs. VI and IX, is normally pressed by the spring F or F' so that it acts as a two-way lock between the reentrant portion of the surface of the hub D, which is the operated part, and the stationary casing A'. The first movement of the operating lever C in any case effects a release of the cam, and after this slight differential movement which holds the locking ball or conical means out of engagement, the further movement of lever C rotates the operated part any desired extent. Immediately upon letting go of the handle C, the spring action sets the single operating means, whether ball or cone, into the locking position so that any tendency of the operated part to move is resisted by the cam action between the hub D and the fixed casing A and the intermediate single locking member.

As shown in Fig. 5 there may be two locking rollers, and similarly two or more locking balls or locking rollers may be used, each having its suitable releasing means. While the reentrant angle on the hub D as shown gives a considerable obliquity to the locking face with respect to the stationary casing A', it is obvious with suitable preparation of parts the reentrant

angle may be very shallow, or may even consist simply of a slabbed-off or sliced-off portion of the surface of the hub D.

While I have shown and described specific forms of my own invention, I do not thereby limit myself to such particular constructions as various modifications are possible without departing from the spirit of my invention.

What I claim and desire to secure by Letters Patent is:

1. In a locking device in a two-way locking mechanism, a stationary member, a member to be moved concentric with said stationary member, a single locking member adapted when in one position to lock said parts against relative movement in either direction by movement substantially parallel with the axis of rotation, an operating means adapted to release said locking member from its locking position and by further movement to move said operated member.

2. In a locking device, a cam faced rotary part to be operated, an operating lever pivoted on the same axis as said operated part, a stationary cam faced casing having its cam face opposed to the cam face on said operated part, said cam face portions inclined to each other, a single cam locking device, automatic means for forcing said locking device in a direction parallel to the axis of rotation of the operated member, means associated with said operating lever for moving said locking device in opposition to said automatic locking means.

3. In combination in a locking device for two-way operation of a control lever, a rotary operated part, a control lever having its axis of movement co-incident with the axis of the operated part, means associated with the operated part and the control lever whereby a slight relative movement is permitted, a fixed member concentric to the operated part, a locking wedge cam faced part of said operated part juxtaposed to said fixed member whereby a single wedge in one position automatically effects the operating of said locking part with respect to said fixed member against movement in either direction.

4. In combination in a two-way locking device, an operated part, an operating handle, a fixed casing, spring connections between said operating handle and operated part, a conical locking roller adapted to engage a fixed member and said operated part, whereby said spring connections between the operating handle and operated part force said locking device into operative position, whereby a single locking device holds said operated part with respect to said fixed member against rotation in either direction.

5. In combination in a two-way locking device, an operated part, an operating handle, a fixed casing, a locking member be-

tween said fixed casing and operated part adapted in its normal position to lock the operated part against movement of rotation in either direction, means for normally 5 moving said member in a direction transverse to the movement of rotation of said operated part into said double locking position, connections between said locking member and operating handle whereby the initial movement of the operating handle 10 releases said locking means, for the purpose described.

6. An automatic locking device for rotary parts, an operated member and an operating member mounted to turn about a common axis, a stationary casing concentric with said common axis, a member adapted 15

to lock said operated member to said stationary member against rotation in either direction, means associated with said operating member adapted to move said locking member substantially parallel with the common axis of the other members, whereby said locking member is removed from its locking position by a slight movement of 20 the operating part with relation to the 25 operated part.

Signed at East Boston, Mass., this 26th day of August, 1909.

ETHELBERT FAVARY.
